UNITED STATES PATENT OFFICE.

WILLIAM MANTEUFFEL, OF ST. PAUL, MINNESOTA.

REFRIGERATOR.

Application filed August 3, 1920. Serial No. 400,912.

To all whom it may concern:

Be it known that I, WILLIAM MANTEUFFEL, a citizen of the United States, residing at St. Paul, in the county of Ramsey and State of Minnesota, have invented a new and useful Improvement in Refrigerators, of which the following is a specification.

My invention relates to refrigerators, the primary object of which is in a refrigerator 10 designed to intake fresh air at the ice chamber and pass the same through the provision chamber below the ice chamber, thence through the provision chamber at the bottom and side of the ice chamber and out of the 15 uppermost part of the provision chamber. In this manner fresh, pure air is circulated through the refrigerator and the circulation of the air through the same provides a refrigerator which is capable of preserving 20 food a great deal longer than where dead air is contained and held enclosed in the same.

The invention provides a peculiar construction for directing or admitting air from the outer atmosphere into the refrigerator 25 in a manner in which is most effective without undue action on the ice contained therein, thus preventing the unnecessary or rapid consumption of ice in the refrigerator.

A further object of the invention is to provide a side or division wall which is closed or sealed at the top to divide the upper portion of the refrigerator while the same is open at the bottom to allow the air from the ice chamber and intake passageway to pass 35 into the main provision chamber and out at the upper extremity of the same. Heretofore in the manufacture of refrigerators it has been desirable to provide the division wall with a passageway at the top and bottom to 40 allow the air concealed in the refrigerator to circulate through the ice and provision chambers. This principle is contrary to the construction of my refrigerator as it would not be practical to have the division wall 45 open at the top in my device.

Further objects and peculiar features of the invention will be more fully described and set forth in the specification and claims.

In the drawing:

50 Figure 1 is a front view of my refrigerator partly illustrated in cross section.

Figure 2 is a side sectional elevation on the line 2—2 of Figure 1.

55 Figure 3 is a sectional detail on the line 3—3 of Figure 1.

Figure 4 is a diagrammatic view of a show

case refrigerator with a central ice chamber partly illustrated in section.

Figure 5 is a diagrammatic view of the so-called butcher cooler partly illustrated in 60 cross section.

In the drawings, the refrigerator A illustrated in Figures 1 to 3 is of ordinary outer cabinet construction, having a side ice chamber B, which is separated from the main provision chamber C by the partition or wall 65 10. A provision chamber D is formed directly below the ice chamber B through which the drain pipe 11 from the removable drip pan 12 extends to drain the water from the ice in the ice chamber to discharge the same outside of the refrigerator in the ordinary manner.

The partition or division wall 10 extends to the ceiling 13 of the refrigerator A to 75 seal and separate the upper portion of the provision chamber from the refrigerator chamber so that there is no connection or air passageway from one to the other, excepting below the lower edge 14 of the division wall 80 10. This construction causes the cold air from the ice in the chamber B to be passed through the grate on which the ice rests and below the lower edge 14, through the chamber D and into the chamber C, while none of 85 the air from the chamber C is passed back into the ice chamber, either through the wall 10 or over the top of the same, as has ordinarily been done heretofore. In this construction my refrigerator is entirely different in 90 operation than other refrigerators used heretofore.

An opening 15, which is covered by a suitable protecting mesh, allows fresh air to enter the passageway 16, which extends along the top and back of the refrigerator chamber and out of the passageway 17, just below the ice grate 18 to admit fresh air from the outer atmosphere into the refrigerator A directly below the ice chamber B.

A frusto-pyramidal shaped pan 19 concentrates the water from the grate 18 so that the same can be directed into the removable pan 12.

An outlet passageway 20 is positioned in 105 the uppermost position in the chamber C to allow warm air to pass from the inner part of the refrigerator to the outer atmosphere. The opening 20 is covered on the outside with a suitable protecting mesh in a similar 110 manner as the protection for the opening 15. It is desirable to have the opening 20 posi-

tioned as high as possible in the chamber C to allow the warm air and odors to be passed out of the provision chamber, it being readily understood that the amount of air passing out of the opening 20 will be in proportion and in accordance with the ingress of fresh air from the outer atmosphere through the opening 15 and the passageway 16, so that in the operation of the refrigerator A, the ice 5 in the chamber B will sufficiently cool the passageway 16, which is separated from the ice chamber B by the metal lining of the refrigerator B, thus readily transmitting cold air to the passageway 16 and causing the attraction of the air in the outer atmosphere into the passageway 16 and down out through the opening 17, as indicated by the arrows in 10 Figure 2, in this manner introducing fresh air into the refrigerator provision chamber 15 and forming a circulation by allowing warm air to pass out through the opening 20.

The construction of the passageway 16 prevents any inflow of warm air being directed against the ice, thus in no way tending to melt the ice with unnecessary rapidity, while on the other hand, the introduction of fresh air from the outer atmosphere in connection with the opening 20, allows 25 fresh air to be introduced and circulated 30 through the provision chamber C. The fresh air entering the passageway 16 is sufficiently cool as it passes through the passageway 16 so that by the time it egresses from the opening 17 it is materially reduced 35 in temperature and at this point it comes in contact with the cold air from the chamber B, in this manner reducing the fresh air to the proper temperature to cool the provision chamber of the refrigerator A. The circulating air through the provision chambers 40 has a tendency to equalize the temperature in the refrigerator A and thus gives a much lower temperature at the uppermost portion of the provision chamber C than is attainable where the same air circulates continuously through the chambers of the refrigerator, at the same time introducing the desired amount of fresh, pure air from the outer atmosphere. It is a wellknown fact 45 in refrigerators that where fresh air can be circulated from the outer atmosphere into the refrigerator without interfering with the refrigeration of the same that a much more effective and practical refrigeration can be 50 obtained than where dead air is confined in the refrigerator and caused to circulate over the provisions and ice contained in the same.

In a practical test of this refrigerator I have found that fresh air will readily enter 60 through the passageway 15 and the warm air from the provision chamber will be passed out of the opening 20. In fact, the draft of air passing into the passageway 15 will cause a light piece of paper to be drawn 65 toward and against the opening 15, while a

similar piece of paper is blown away from the opening 20. The closed division wall 10, especially at the top with an opening at the bottom, forces the draft in the direction toward the opening 20 and as the cold air 70 presses the warm air out of the upper portion of the chamber C, it will be readily understood that the same amount of air as is passed out will be drawn in through the opening 15 and passageway 16. 75

In Figure 4 a show case refrigerator is illustrated diagrammatically, the ice chamber B being positioned centrally in the same, while the provision chambers C are located on either side and the partitions 10 extend downward from the ceiling of the provision chambers, leaving passageways below the lower edge 14 of the same to allow the cold air from the ice chamber to be passed into the provision chamber C. An inlet passageway 15 allows fresh air to be admitted 80 into the chamber D directly below the ice chamber, as is illustrated in Figure 1, while outlet passageways 20 are provided on either end at the uppermost portion of the provision chamber C. This construction performs the same functions as the refrigerator 85 illustrated in Figures 1 to 3.

Figure 5 illustrates diagrammatically a so-called butcher cooler with the overhead 90 ice chamber B extending across and above the main provision chamber C, while an inlet passageway 15 is provided which connects the passageway 16 to pass fresh air 95 from the outer atmosphere into the provision chamber C from the passageway 16 out of the opening 17 in a similar manner as illustrated in Figure 1. In this construction a passageway 22 extending upwardly from the chamber C connects the provision chamber C at the opposite side to the inlet opening 17 with the outlet passageway 20 so as to allow the warm air to be passed out of the refrigerator. This construction gives the 100 same functions as that performed by the constructions hereinbefore illustrated. The inlet and outlet openings 15 and 20 are positioned above the upper doors in the construction illustrated in Figure 1 and are 105 positioned at the uppermost portion of the ice and provision chambers, respectively, each of the constructions being positioned at an equal height to each other where it is possible to provide an even circulation 110 through the refrigerator. 115

It will be readily seen that the fresh air from the outer atmosphere in the construction of the refrigerators illustrated is passed through the refrigerator chamber without 120 coming in direct contact with the ice and is discharged into the provision chamber at a colder temperature than when it enters the inlet passageway and allows the free circulation of air through the provision chamber passing out through the opening 20, thus 125 130

maintaining a circulation of fresh, cool or refrigerating air through the provision chamber of the refrigerator at all times. The functions of each of the constructions 5 illustrated are identical to accomplish the principal of my invention.

I have illustrated particular constructions of refrigerators in the drawings but I desire to have it understood that these are 10 only illustrative and that the invention can be carried out by other means and applied to uses other than those above set forth within the scope of the following claims:

1. A refrigerator comprising a casing 15 having a partition extending downwardly from the upper portion of said casing to form an ice compartment on one side thereof and a food compartment to the side of and below said ice compartment, an air inlet on the front of said casing on one side of said partition, an air outlet on the front of said casing on the opposite side of said partition communicating with said food compartment, and a duct connected with said 20 inlet running along the under surface of said casing within the ice compartment, and from thence downwardly along the inner surface of the back of said casing and discharging below said ice compartment into 25 said food compartment.

2. A refrigerator comprising a casing, an ice chamber positioned in an upper corner of said casing and a food compartment situated below and to the side of said ice compartment, an air inlet positioned in the 30 front of said casing opposite the upper portion of said ice compartment, a duct connected with said inlet extending along the upper portion of said ice compartment and from thence along the back of the same and discharging below said ice compartment into 35 said food compartment, and an outlet formed in the front of said casing adjacent said inlet leading into the upper portion of 40 said food compartment.

3. A refrigerator comprising a casing containing an ice chamber positioned at an upper portion thereof, a food compartment

extending below and to the side of said ice chamber an air inlet in said casing at the upper portion thereof opposite said ice chamber, means for conducting air from said inlet around said ice chamber and discharging it into said food compartment below the ice chamber, and an air outlet directly communicating with food compartment at the side opposite said ice chamber at the upper portion thereof.

4. A refrigerator having an ice chamber, a fresh air passageway passing over said ice chamber and down the side thereof to admit fresh air from the outer atmosphere directly below the ice chamber, a partition having a closed upper end adapted to separate the ice chamber from the provision chamber of 60 said refrigerator, a passageway below said partition to admit refrigerating air from said ice chamber and said inlet passageway to the provision chamber and an outlet passageway provided at the upper extremity of 65 the provision chamber to allow air to be circulated from below the ice chamber into the provision chamber and out of the upper extremity of the provision chamber, whereby a circulation of fresh, refrigerating air is 70 continuously passed through said provision chamber and the warm air out of the same to the outer atmosphere.

5. A refrigerator comprising a casing containing an ice chamber positioned at an upper portion thereof, a food compartment extending below and to the side of said ice chamber, an air inlet in the front of said casing at the upper portion thereof opposite said ice chamber, a pipe for conducting air 80 from said inlet across the top of said ice chamber down the rearward wall of the same, and an outlet to said pipe for discharging the air immediately below said ice chamber in the portion of the food compartment beneath the same, and an air outlet 85 directly communicating with the food compartment in the side opposite to said ice chamber on the front of the refrigerator adjacent said inlet opening.

WILLIAM MANTEUFFEL.
